MULTIPLE BREAK GAS BLAST CIRCUIT
BREAKER

Hans Thommen, Baden, Switzerland, assignor to
Aktiengesellschaft Brown, Boveri, & Cie.,
Baden, Switzerland, a joint-stock company

Application March 25, 1941, Serial No. 385,170
In Switzerland March 9, 1940

7 Claims. (Cl. 200—148)

This invention relates to circuit breakers and more particularly to multiple break gas blast circuit breakers.

There is a non-uniform voltage distribution along the several current interrupting points of a multiple break circuit breaker of the type having a plurality of arcing contacts electrically and spatially in series. This uneven voltage distribution is particularly disadvantageous in circuit breakers in which the arcing contacts are subjected to a blast of gas under pressure to extinguish the arcs, since it results in a decrease in the rupturing capacity of the circuit breaker and an increase in the consumption of the arc-extinguishing medium.

In order to overcome these disadvantages and to improve the capacity of the circuit breaker it has already been proposed that resistors or capacitors be connected in parallel with each arcing contact gap. When the circuit breaker is opened, the residual current through the impedances is quite small and may be interrupted for instance by a voltage isolating switch arranged in series with the multiple interruption points. The aforementioned impedances or damping means are located either inside or outside of the switch chambers enclosing the arcing contacts and can be constructed as integral part of the switch chambers themselves or as separate devices to be fixed to the chambers.

An object of the present invention is to improve the rupturing capacity of gas blast circuit breakers with multiple interruption by other very simple means and at the same time to achieve a more economical operation of the apparatus. According to the invention, this is attained by dimensioning each point of current interruption for a different rupturing capacity, so that those points of interruption which are subjected to the highest stresses when opening the circuit are dimensioned for the largest rupturing capacity.

In some cases it is sufficient if, in circuit breakers having a plurality of switching points arranged in series, only the sets of arcing contacts at each end of the breaker are dimensioned for a higher interrupting capacity than the remaining ones of the series. It is, however, also possible to design the circuit breaker so that at each end the two outer switching points are dimensioned for a higher rupturing capacity than the remaining contact points. The rupturing capacity of the various switching points can also be uniformly graded. This grading is achieved according to the invention by constructing the outer or end points of interruption so as to be

capable of dealing with the highest voltages to be interrupted while the remaining points of interruption are so dimensioned that their rupturing capacity decreases uniformly from both ends towards the center of the circuit breaker.

The rupturing capacity at each point of current interruption is determined by the size of the arcing contacts and the stroke of the movable contact. For instance, in order to increase the rupturing capacity of an interruption point in a circuit breaker provided with hollow arcing contacts, the bore of the hollow contact and/or the stroke of the movable contact can be correspondingly increased.

15 By designing the points of interruption in the manner described so as to have different dimensions, it is possible to ensure that when extinguishing the arcs each switch element or point of interruption requires only an amount of pressure gas sufficient for the rupturing capacity in question; there is therefore no waste as regards the arc-extinguishing medium. Furthermore, it is also possible to strengthen the insulation of the switch elements in accordance with the power 20 to be interrupted.

The objects and advantages of the invention will be apparent from the following specification when taken with the accompanying drawing in which:

25 30 Fig. 1 is a somewhat diagrammatic vertical central section through an embodiment of the invention;

35 Fig. 2 is a fragmentary vertical section, on an enlarged scale, through the lower arcing chambers of the circuit breaker of Fig. 1; and

Figs. 3 and 4 are diagrammatic central vertical sections through other embodiments of the invention.

40 As shown in Fig. 1, a multiple break circuit breaker of the general type contemplated by the invention may comprise a series of vertically arranged arcing chambers, identified generally by reference numerals 1a to 1g, respectively, that each house a set of gas blast arcing contacts.

45 Hollow insulators 2 form the outer walls of the several chambers, and metal plates or castings 3 each rest upon one insulator and support the next higher insulator to form the transverse walls that separate the chambers from each other.

50 The line connections L, L' are made to a terminal 4 of the cap member 5 that rests upon the top plate 3, and to the base casting 6 that forms the lower wall of the end arcing chamber 1a. The base 6 is mounted at the top of a hollow insulator column, not shown, through which a pressure

gas is supplied to separate the arcing contacts and to extinguish the arcs drawn between the separating contacts. The pressure gas enters the end chamber 1a through openings 7 in the base 6, and flows from one chamber to the next through ports 8 in the transverse wall plates 3.

Each plate 3 has a passage 9 extending laterally from the outer edge of the plate to the central part where it opens downwardly through a nozzle contact that cooperates with a movable 10 pin contact carried by the next lower plate 3 or, in the case of the end chamber 1a, by the base plate 6. The nozzle contacts and the movable pin contacts of the several arcing chambers 1a to 1g are identified by reference numerals 15 10a-10g and 11a-11g, respectively.

In the embodiment shown in Figs. 1 and 2, the power rupturing capacities of the cooperating arcing contacts of all intermediate arcing chambers 1b-1f are the same, and only the end arcing chambers 1a and 1g are designed for a greater rupturing capacity. The several transverse wall plates 3 are preferably of identical design, as shown in Fig. 2, and the dimensions of the several nozzle contacts are varied by a selection of the nozzle bushings 12a, 12b, etc., that are threaded into the nozzle openings of the metal plates 3. The contour of the cooperating pin contacts is adjusted to conform to the geometry of the different nozzle contacts by interchangeable caps 13a, 13b, etc., that are threaded upon the ends of the movable contacts. The movable contacts are slidable in cylinders 14 that project above the base 6 and all plates 3 except the top plate. The movable contacts are normally retained in circuit closing position by springs 15 and are forced downward by pressure gas admitted to the several arcing chambers. Stop pins are mounted within the cylinders 14 to limit the opening movement of the several pin contacts. The stop pins 16a and 16g of the end chambers are somewhat shorter than the stop pins 16b to 16f of the intermediate arcing chambers.

Inspection of Fig. 2 will show that the nozzle contact bushing 12a has a substantially larger bore than that of the next higher nozzle contact bushing 12b. The lowermost arcing chamber therefore has a greater rupturing capacity than the adjacent arcing chamber. Similarly, the power interrupting capacity of the cooperating contacts 10g, 11g of the top arcing chamber is greater than that of the next lower and all intermediate arcing chambers.

The general structure of the circuit breakers of Figs. 3 and 4 is similar to the Fig. 1 embodiment, but the several embodiments differ from each other in the design of the relative power rupturing capacities of the several sets of arcing contacts. Corresponding reference numerals are applied to those elements of Figs. 3 and 4 that are, or may be, identical with the similar parts of Fig. 1.

In the Fig. 3 embodiment, the two outer sets of arcing contacts at each end of the circuit breaker are designed for one rupturing capacity, and the intermediate sets of contacts are designed for a smaller rupturing capacity. The cooperating nozzle contacts 10 and movable pin contacts 11 of the end chambers 31a, 31b and 31f, 31g are therefore somewhat larger than the sets of nozzle and pin contacts 10', 11', respectively, of the intermediate arcing chambers 31c to 31e.

In Fig. 4, the rupturing capacities of the series of arcing contacts within the chambers 41a-41g are progressively graduated from a maximum

value at the outer sets of contacts to a minimum value for the arcing contacts of the central arcing chamber 41d. This progressive grading of the dimensions of the nozzle contacts 42a-42g and of the pin contacts 43a-43g is shown in the drawing.

The method of operation is, in general, the same as in prior multiple break gas blast circuits of the type in which impedances were shunted across the points of circuit interruption to establish a preselected voltage gradient along the several arcing contacts. The breakers are opened by admitting a pressure gas to the arcing chambers through the openings 7 of the base plate 6. The pressure gas flows upwardly through the ports 8, and forces the several pin contacts away from the cooperating nozzle contacts. The pressure gas then escapes through the nozzle contacts and lateral passages as high velocity blasts that extinguish the arcs. The voltage gradient along the series of gaps is not uniform when the arcing contacts open under load but, as described above, the several sets of arcing contacts are designed for a higher rupturing capacity at the points of higher electrical stress. Relatively large quantities of the pressure gas are discharged across and around the relatively high power arcs that are drawn between the outer sets of arcing contacts, and lesser quantities of pressure gas are used to extinguish the lower power arcs that are drawn between the intermediate sets of arcing contacts.

The rupturing capacities were adjusted, in the illustrated embodiments, by varying both the bore size of the nozzle contacts and the stroke of the pin contacts. Greater design latitude is had when both of these factors are variable, but it is to be understood that the contacts may be designed for a change in only the bore size of the nozzle contact or only the stroke of the pin contact.

I claim:

1. A multiple break gas blast circuit breaker of the type including a plurality of sets of cooperating arcing contacts arranged electrically and spatially in series, terminal connections for an electrical line at the outer contacts of said serially arranged sets, one contact of each set being movable by pressure gas to separate that contact from the cooperating contact and one contact of each set being a nozzle contact through which the pressure gas escapes as an arc-extinguishing gas upon the separation of the cooperating contacts, characterized by the fact that the sets of arcing contacts at each end of the series include means for establishing through the nozzle contacts thereof arc-extinguishing blasts of greater power rupturing capacity than the arc-extinguishing blasts established through the nozzle contacts of the intermediate sets of arcing contacts.

2. A multiple break gas blast circuit breaker of the type including a plurality of sets of cooperating arcing contacts arranged electrically and spatially in series, one contact of each set being a nozzle contact and one contact of each set being movable by pressure gas to separate the cooperating contacts, characterized by the fact that the nozzle contacts of the cooperating sets of contacts at the outer ends of the series have bores of larger size than the bore of the nozzle contact of an intermediate set of cooperating contacts.

3. A multiple break gas blast circuit breaker of the type including a plurality of sets of co-

operating arcing contacts arranged electrically and spatially in series, one contact of each set being a nozzle contact and one contact of each set being movable by pressure gas to separate the cooperating contacts, characterized by the fact that the nozzle contacts of each outer set of cooperating contacts at the respective ends of the series have bores of larger size than the bores of the nozzle contacts of all intermediate sets of cooperating contacts.

4. A multiple break gas blast circuit breaker of the type including a plurality of sets of cooperating arcing contacts arranged electrically and spatially in series, one contact of each set being a nozzle contact and one contact of each set being movable by pressure gas to separate the cooperating contacts, characterized by the fact that the nozzle contacts of the two outer sets of cooperating contacts at the respective ends of the series have bores of larger size than the bores of the nozzle contacts of all intermediate sets of cooperating contacts.

5. A multiple break gas blast circuit breaker of the type including a plurality of sets of cooperating arcing contacts arranged electrically and spatially in series, one contact of each set being a nozzle contact and one contact of each set being movable by pressure gas to separate the cooperating contacts, characterized by the fact that the nozzle contacts of the several sets

of cooperating contacts have bores that vary in size progressively from a maximum at the outer nozzle contacts to a minimum at the centrally located nozzle contact.

6. A multiple break gas blast circuit breaker of the type including a plurality of sets of cooperating arcing contacts arranged electrically and spatially in series, one contact of each set being a nozzle contact and one contact of each set being movable by pressure gas to separate the cooperating contacts, characterized by the fact that means is provided to limit the opening movement of the movable contacts of the intermediate sets of cooperating contacts to a lesser value than the opening movement of the movable contacts of the outer sets of cooperating contacts.

7. A multiple break gas blast circuit breaker of the type including a plurality of sets of cooperating arcing contacts arranged electrically and spatially in series, one contact of each set being a nozzle contact and one contact of each set being movable by pressure gas to separate the cooperating contacts, characterized by the fact that means is provided to limit the opening movement of the movable contacts of the intermediate sets of cooperating contacts to a lesser value than the opening movement of the two outer sets of cooperating contacts at each end of the series.

HANS THOMMEN.
